(57) **CLAIM**

The ornamental design for an off-trigger locator for a firearm, as shown and described.

DESCRIPTION

FIG. 1 is a partial right side elevational view of a firearm showing an off-trigger locator of our new design comprising a circular depression with raised center dot on a right side of a frame of the firearm;

FIG. 2 is a partial left side elevational view of the firearm of FIG. 1;

FIG. 3 is a partial perspective view of the off-trigger locator of the firearm of FIG. 1;

FIG. 4 is a partial alternate perspective view of the off-trigger locator of the firearm of FIG. 1;

FIG. 5 is a partial alternate perspective view of the firearm of FIG. 1;

FIG. 6 is a partial alternate perspective view of the firearm of FIG. 1;

FIG. 7 is an enlarged partial cross-section view of the off-trigger locator of the firearm of FIG. 1 taken along lines 7-7 of FIG. 1;

FIG. 8 is a partial left side elevational view of a firearm showing an alternate embodiment of an off-trigger locator of our new design comprising a circular depression with raised center dot on a left side of a frame of the firearm;

FIG. 9 is a partial right side elevational view of the firearm of FIG. 8;

FIG. 10 is a partial perspective view of the firearm of FIG. 8;

FIG. 11 is a partial alternate perspective view of the firearm of FIG. 8;

FIG. 12 is a partial perspective view of the off-trigger locator of the firearm of FIG. 8;

FIG. 13 is a partial alternate perspective view of the off-trigger locator of the firearm of FIG. 8;

FIG. 14 is an enlarged partial cross-section view of the off-trigger locator of the firearm of FIG. 8 taken along lines 14-14 of FIG. 8;

FIG. 15 is a partial right side elevational view of a firearm showing an alternate embodiment of the off-trigger locator of our new design comprising a circular depression with raised center dot on a right side of a frame of the firearm;

FIG. 16 is a partial left side elevational view of the firearm of FIG. 15 showing an off-trigger locator of our new design comprising a circular depression with raised center dot on a left side of a frame of the firearm;

FIG. 17 is a partial alternate perspective view of the off-trigger locator of the firearm of FIG. 15;

FIG. 18 is a partial alternate perspective view of the off-trigger locator of the firearm of FIG. 15;

FIG. 19 is a partial alternate perspective view of the off-trigger locator of the firearm of FIG. 15;

FIG. 20 is a partial alternate perspective view of the off-trigger locator of the firearm of FIG. 15;

FIG. 21 is an enlarged partial cross-section view of the off-trigger locator of the firearm of FIG. 15 taken along lines 21-21 of FIG. 15;

FIG. 22 is a partial right side elevational view of a firearm showing an off-trigger locator of our new design comprising a circular convexity with raised center dot on a right side of a frame of the firearm;

FIG. 23 is a partial left side elevational view of the firearm of FIG. 22;

FIG. 24 is a partial perspective view of the off-trigger locator of the firearm of FIG. 22;

FIG. 25 is a partial alternate perspective view of the off-trigger locator of the firearm of FIG. 22;

FIG. 26 is a partial alternate perspective view of the firearm of FIG. 22;

FIG. 27 is a partial alternate perspective view of the firearm of FIG. 22;

FIG. 28 is an enlarged partial cross-section view of the off-trigger locator of the firearm of FIG. 22 taken along lines 28-28 of FIG. 22;

FIG. 29 is a partial left side elevational view of a firearm showing an alternate embodiment of an off-trigger locator of

our new design comprising a circular convexity with raised center dot on a left side of a frame of the firearm;

FIG. 30 is a partial right side elevational view of the firearm of FIG. 29;

FIG. 31 is a partial perspective view of the firearm of FIG. 29; FIG. 32 is a partial alternate perspective view of the firearm of FIG. 29;

FIG. 33 is a partial perspective view of the off-trigger locator of the firearm of FIG. 29;

FIG. 34 is a partial alternate perspective view of the off-trigger locator of the firearm of FIG. 29;

FIG. 35 is an enlarged partial cross-section view of the off-trigger locator of the firearm of FIG. 29 taken along lines 35-35 of FIG. 29;

FIG. 36 is a partial right side elevational view of a firearm showing an alternate embodiment of the off-trigger locator of our new design comprising a circular convexity with raised center dot on a right side of a frame of the firearm;

FIG. 37 is a partial left side elevational view of the firearm of FIG. 36 showing an off-trigger locator of our new design comprising a circular convexity with raised center dot on a left side of a frame of the firearm;

FIG. 38 is a partial alternate perspective view of the off-trigger locator of the firearm of FIG. 36;

FIG. 39 is a partial alternate perspective view of the off-trigger locator of the firearm of FIG. 36;

FIG. 40 is a partial alternate perspective view of the off-trigger locator of the firearm of FIG. 36;

FIG. 41 is a partial alternate perspective view of the off-trigger locator of the firearm of FIG. 36; and,

FIG. 42 is an enlarged partial cross-section view of the off-trigger locator of the firearm of FIG. 36 taken along lines 42-42 of FIG. 36.

The dashed lines within the figures are for illustrative purposes only and form no part of the claimed design.
